UNITED STATES PATENT OFFICE.

WILLIAM F. LAUTENSCHLAGER, OF CINCINNATI, OHIO.

FOLDING-MACHINE.

1.121.851.

Specification of Letters Patent. Patented Dec. 22, 1914.

Application filed February 12, 1914. Serial No. 818,250.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Folding Machines, of which the following is a specification.

My invention relates to folding machines
10 applicable for folding the edges of flexible
material, such as leather, cloth or the like.

material, such as leather, cloth, etc.

It is the object of my invention to provide novel means in a machine of the character mentioned, whereby strain tending to stretch the curling edge of the material at the folder, fold-presser engaged during the curling of the material in the formation of a fold is avoided or minimized and the normal length of the curl formed in the formation of the folding is reduced; further to provide novel means whereby the edge of the material is maintained in guided relation with a gage; further to provide novel means whereby a reverse curl is imparted to the edge of the material in advance of the upward curl formed by the folder, whereby the guided edge of the material is depressed into range with the gage; further to provide a fold-presser so arranged as to press the margin being folded with a forward pressing face extending selectively recedingly or substantially directly crosswise of the margin being pressed when in fold-pressing relation; further to provide a fold-presser having an initial pressing portion for the margin of the material being folded shiftable under the control of the operator while the material is being folded for presenting said initial pressing portion to the margin being folded in different directions crosswise of the width of the margin being folded with relation to the direction of the feeding movement when in fold-pressing position; further to provide novel means for manually shifting the reciprocating initial pressing portion of the fold-presser during the folding movement of the material through the machine; further, to provide novel means for manually adjusting the limit of movement of said initial pressing portion of the fold-presser during the operation of the machine; and, further, to provide novel means for adjustably locating the path

of reciprocating movement of the reciprocating forward fold-pressing portion of the 55 fold-presser.

The invention will be further readily understood from the following description and claims, and from the drawings, in which latter:

Fig. 1 is a side elevation of my improved device. Fig. 2 is a front end elevation of the same. Fig. 3 is a rear end elevation of the same. Fig. 4 is a vertical cross-section taken on the line 4—4 of Fig. 1, showing the driving connections for the oscillating knife and fold-presser. Fig. 5 is a bottom view of the head-end of the bed. Fig. 6 is a plan view of the operating mechanism at the head-end of the machine, with the overhanging bracket removed and the presser-foot post and feeding foot stem broken away. Fig. 7 is a similar view showing a piece of material with a straight edge being fed through the machine and folded, the movable fold-presser portion being in retracted position. Fig. 8 is a similar view showing a piece of material with a concave edge being fed through the machine. Fig. 9 is a similar view, showing a piece of material with a convex edge being fed through the machine, with the movable portion of the fold-presser in advanced position. Fig. 10 is a similar but enlarged view, partly broken away, showing a piece of material with a straight edge being fed through the machine, and showing the movable portion of the fold-presser in raised relation and in retracted position and the curl portion of the fold being made when said movable portion is in retracted position, in full lines, and indicating in dotted lines the relations which the forward wall of the movable portion of the fold-presser and the curl portion of the fold would assume if said forward wall of said movable portion were advanced in folding straight edge material and indicating the change in relation which the curl portion of the fold would assume with relation to the gage. Fig. 11 is a vertical section, parallel to the line of feed, taken on the line 11—11 of Fig. 10, indicating the action of the feeding and folding devices on the material, and the lay given to the margin of the material by the raised portion of the material support. Fig. 12 is a vertical section of the same, taken on the

line 12—12 of Fig. 10, with the feeding foot in raised position. Fig. 13 is a cross-section of the same, taken on the line 13—13 of Fig. 10. Fig. 14 is a detail of the controlling mechanism for the adjustable portion of the fold-presser, taken on the line 14—14 of Fig. 9. Fig. 15 is a bottom view of the fold-pressing portion of the fold-presser, with the movable part thereof in advanced position; 10 and, Fig. 16 is a rear elevation of the same.

In the present exemplification, the folding machine comprises feeding means for the material, exemplified as a feeding foot 21 coöperating with a roller 22, a presser-foot 23 adapted to hold the material in place between feeding movements, cutting or snipping means adapted to provide the edge of the material being folded with cross-cuts or snips when such cutting or 20 snipping is desired and comprising an upper cutter 24 and a lower cutter 25, a folder 26 adapted to curl upwardly the margin to be folded, and a fold-presser 27 adapted to press the folded margin toward the body of 25 the material, the edge of the material being fed against a suitable gage 28.

31 represents the frame of the machine, which comprises an overhanging arm 32, preferably forming a so-called goose-neck 30 frame, having a head 33.

The feeding-foot is arranged to be moved downwardly and forwardly for the feeding movement and upwardly and rearwardly for the retracting movement, for intermittently feeding the material. The roller 22 is rotatable about a pivot-screw 34 secured to the table-portion 35 of the frame. The presser-foot is arranged to bear upon the material being fed through the machine during the retracting movements of the feeding foot, and the presser-foot is arranged to be held in raised position during the feeding movement of the material.

Suitable means are provided for operating the feeding foot and the presser-foot, exemplified as follows: 36 is a drive-shaft journaled in bearings 37, 38, of the main frame. It has suitable driving means thereon, shown as a pulley 39. 41 and 42 are rock-shafts. A lever 43 is pivoted on a stud 44 to the main frame. The drive-shaft is provided with an eccentric 45 which co-operates with the walls of a coacting cam-block 46 on the lever. The lever comprises 55 an arm 47 which is articulated at 48 with a link 49, articulated at 50 with an arm 51 on a hub 52 rockable about the rock-shaft 41 and provided with a segment-gear 53 inmeshing with a segment-gear 54 fast on the rock-shaft 42. The articulation 48 is adjustable lengthwise of the slot 55 for varying the extent of rocking movement of the arm 51, and consequently varying the lengths of steps of the feeding-foot. The rock-shaft

42 further has a segment-gear 57 fast on its 65 forward end, which meshes with a rack 58 fast on a slide-frame 59 for the feeding-foot, 70 slideable laterally on guide-rods 60 fast in the head of the frame.

The feeding-foot 21 is on a stem 61 which 70 reciprocates up and down in bearings 62 in the slide-frame 59. The stem has a guide 63 arranged to be adjustably clamped at suitable positions lengthwise thereof by means of a clamp-bearing 64. This guide 75 has a guideway 65 in which a pin 66 on a rocker-arm 67 is received, the rocker-arm being fast on the rock-shaft 41.

The rock-shaft 41 is provided with a segment-gear 68 fast thereon with which a 80 rack-bar 69 meshes, the rack-bar being guided in a bearing 70 of the main frame and by a slot 71 through which the drive-shaft is received. A cam 72 is fast on the drive-shaft and coöperates with a roller 73 85 on the rack-bar. A spring 74 is received about the rack-bar between the bearing 70 and a collar 75 secured to the rack-bar.

The spring 74 causes depression of the 90 rack-bar and coaction between the roller 73 and the cam 72 for causing longitudinal movement of the rack-bar and consequent rocking movement of the rock-shaft 41, which causes a gradual rising movement of the feeding-foot during the retracting movement thereof, caused by the eccentric-portion 76, and a comparatively rapid descent of the feeding-foot at the end of said 95 retracting movement, caused by the eccentric-portion 77, the feeding movement taking place while the concentric-portion 78 coacts with the roller. The spring causes yielding movement of the feeding-foot toward the material and permits yielding movement of the feeding-foot due to inequalities in the 100 thickness of the material being fed through the machine.

The presser-foot is exemplified as mounted on a forwardly extending arm 81 rigidly secured to a reciprocating post 82, reciprocating in bearings 83, 84, in the main frame. The post is held against rotation by means of a positioning screw 85, threaded into the bearing 84, the inner end of the screw being received in a slot 86 extending lengthwise 110 of the post 82. A spring 87 received about the post between the bearing 83 and a collar 88 secured to the post, causes yielding pressure of the presser-foot toward the material. The rock-shaft 41 is provided with a tappet-arm 89 fast thereon, arranged to engage a collar 90 on the post 82, adjustably clamped on the post, for intermittently raising the presser-foot during the operation of the machine.

For manually raising the presser-foot a lever 91 is provided, pivoted to the bearing 84 on a screw 92 and having a knob 93

thereon received between lugs 94 on the presser-foot arm 81, a spring 95 preventing jarring of the lever 91.

The folder 26 is shown as a folding-block 5 secured to the table of the machine by means of a suitable screw 96.

The upper cutter 24 coacts with the lower cutter 25, the cutter 24 being shown as a cutter-blade arranged to be adjustably secured to a lever 103 by means of a clamp-screw 104 received through a slot 105 in the cutter-blade and threaded into the lever. The cutter-lever comprises a hub 106, in the form of a bearing about a cross-shaft 107, 15 located in bearings 108, in the table, an arm 110 to which the cutter-blade is secured, and an arm 111 with which driving connection is had for operating the lever.

The fold-presser 27 is on a fold-presser lever 116. As exemplified, the fold-presser lever comprises a hub 117, in the form of a bearing about a cross-shaft 118, received in bearings 119, in the table, an arm 121, and an arm 122 with which drive-connection is 25 formed for operating the fold-presser.

I have exemplified the knife-lever and fold-presser lever actuated by means of eccentrics on the drive-shaft. Thus the drive-shaft is provided with an eccentric 126 about which an eccentric strap 127 is received. A link 128 extends from this strap and has a ball and socket connection 129 with the knife lever. The drive-shaft is also provided with an eccentric 131 about which 35 a bearing 132 is received. A slide-frame 133 is received about the bearing and has slide-connection therewith, as by means of screws 134 threaded into the side walls of the slide-frame and received slidingly in slots 135 of 40 the bearing 132. A link 136 extends from the slide-frame and has ball and strap connection 137 with the fold-presser lever, forming a ball and socket joint. This link may be in the form of an adjusting screw 45 threaded into a threaded socket 138 in the slide-frame and held in adjusted positions by means of a lock-nut 139.

The pressing force of the eccentric 131 upon the fold-presser is imparted through 50 the medium of a spring 140 between the bearing 132 and the end wall 141 of the slide-frame, so that the pressure exerted by the fold-presser upon the folded margin may be a yielding pressure for permitting 55 the fold-presser to yield to inequalities in the material and to exert a yielding pressure upon the fold for pressing the fold.

The lower cutter is shown in the form of 60 a cutter-block which is movable toward and from the upper cutter for placing the lower cutter into coacting relation with the upper cutter, during which relation a snipping or cutting of the edge of the material will be effected at each oscillating movement of the

upper cutter, as when folding concave 65 curves, (see Fig. 8), or for placing the lower cutter in inactive relation with relation to the upper cutter for permitting the edge of the material to be fed past the cutters without being snipped or cut. 70

I have shown the lower cutter-block on a slide 145, shown as a T-slide, slidable in a guideway 146, and held in said guideway by a plate 147. The cutter-block is adjustably clamped to the slide by means of a screw 148 75 received through a slot 149 in the cutter-block and threaded into the slide. The plate is provided with lugs 151, 152, between which a crank-pin 153 is received, the crank-pin being mounted on a rocker-part 80 154, journaled by a stud 155 in a lug 150 of the table.

An arm 156 is rigid on the rock-shaft and has a link 157 articulated therewith. A spring 158 is received about the link between 85 a bearing 159 through which the link passes, and a collar 160 on said link. A suitable connection, as a rod 161, connects the link with a suitable treadle, indicated at 162, for shifting the cutter-block into inoperative relation during the operation of the machine and the feeding of the material through the machine. The plate 147 is arranged to contact a set-screw 165, for defining the cutting 95 relation of the cutter-block to the upper knife. The set-screw 165 is adjustably positioned in a lug 166 of the table and held in adjusted position by a clamp-nut 167.

I have found that in progressively folding the margin of flexible material, such as 100 leather, cloth or the like, it is desirable to avoid a stretching strain upon the edge of the leather being curled, and for this purpose I have provided the material support with a raised portion, located in advance of 105 the material-supporting faces coacting with the fold-forming means, so as to provide the margin of the material with a reverse curl or fold, as indicated at 168, (see Figs. 7, 8, 9, 10 and 11), in advance of the flexing or 110 upwardly folding or turning margin of the material, indicated at 169, whereby the guided portion 170 of the edge of the material is reflexed or curled or arranged downwardly from the flexed or upwardly 115 turned edge of the folding margin into coaction with the side gage, which is located closely adjacent to the fold-forming instrumentalities, and an upward bulge 171 is formed in the material adjacent to its edge. 120

The side gage 28 in the present exemplification extends from a plate 172 adjustable on the table by means of a clamp-screw 173 screwed into the table through a slot 174 in the plate. 125

The material-support or table is indicated at 176 and is shown as comprising a raised portion 177, (see Figs. 2, 6, 11 and 12),

shown in advance of that portion 178 of the material-support, shown as a depressed portion, with which the presser-foot and the fold-presser coöperate and in the plane of which the feeding-foot operates. This raised portion preferably terminates at the side, adjacent to the side gage, approximately at the normal line of feed, for forming a raised corner 179 (see Fig. 6) in rear of the fold-forming and feeding devices and at the side of the gage. This side edge of the raised portion is approximately in line with the bend 164 in the material at which the margin is folded when folding a straight edge.

A finger 180 is provided, which is arranged to project over the reversely curled part of the margin of the material being folded, for forming a channel thereunder through which the material may pass, and guarding against an accidental up-turning of the edge of the material at the gage. This finger is shown on the presser-foot and is shown secured thereto by means of a clamp-screw 175 threaded into the presser-foot and received through a slot in the finger.

The lower cutter-block preferably forms a material-support for the margin of the material being folded at the side of the raised portion of the material-support, and is preferably higher than the depressed portion of said material-support and lower than said raised portion. Its cutting edge is preferably in rear of the transverse vertical plane in which said raised portion of the material-support is located, so that the edge of the material is arranged at said cutting edge of the cutter-block in a plane parallel to the body of the material for being acted on by the upper cutter-blade, while in said plane, as indicated in Fig. 13.

The retraction of the cutter-block permits the ready flexing of the edge of the material below the horizontal plane of the cutting edge of the cutter-block for insuring that the cutter-blade may continue its oscillations thereabove without cutting or snipping action thereof on the material.

I prefer to form the fold-presser adjustable and so arranged as to press the margin being folded with an initial pressure face extending diagonally to the length of the margin being folded, or at substantial right angles to the length of said margin, the direction in which the initial pressure face extends being preferably under control of the operator while the margin is being folded and determined by the shape of the edge of the margin being folded. For accomplishing this end and for aiding the fold in assuming a natural bend or curl, I prefer to provide the fold-presser with a receding forward pressing wall for the margin being folded for permitting the fold to be partly

formed across the end of the fold-presser in the plane of movement of the fold-presser. This relation of the forward pressing face or wall of the fold-presser is employed when folding material having a straight edge (see Figs. 7, 10 and 11), or a concavely curved edge, (see Fig. 8).

When folding material having an edge with a convex curve, (see Fig. 9), the upwardly curling portion of the fold being made is shortened, for the reason that the edge is outwardly rounded and the fold takes place along a more obtuse angle with relation to said edge. For folding such convex edges it is desirable that the forward pressing face of the fold-presser be advanced for presenting said forward pressing face more nearly in a direction at right angles to the line of feed, and bringing said forward pressing face into more intimate range with the fold being made. The desired degree of the angle of presentation of the forward pressing face is determined by the degree of convexity of the edge of the material being folded. The shorter the radius on which the curve is described the more nearly at right angles to the normal line of feed should the forward pressing face of the fold-presser be presented. I have provided means whereby this adjustment can be effected momentarily by the operator during the formation of the fold. In the present exemplification I have also provided means whereby the amount of movement of the pressing edge of the fold-presser is adjusted, and have provided means whereby this adjustment may be accomplished by the operator either during the operation of the machine or while the machine is at rest, and have further provided means whereby the path, in which the said pressing edge reciprocates, is adjustably fixed, although I do not limit myself to the means herein shown for effecting these purposes.

In the present exemplification the fold-presser comprises a body and a movable part 181 arranged to swing on the body of the fold-presser for presenting its forward wall crosswise of the plane of the edge being folded or presenting said forward pressing wall at various angles with relation to the line of feed across said edge being folded. In the form shown this movable part comprises a wall 182 from the upper end of which a lever 183 extends, a pivot-screw 184 being received through said lever and threaded into the body 185 of the fold-presser, the movable part being pivoted about said pivot-screw. A shelf 186 extends from the lower end of the wall 182 under the body of the fold-presser and is preferably received in a recess 187 in the bottom of said body and has a guiding edge 188 formed on the arc of a circle described from the axis of said pivot-screw 184 as a center,

which coacts with a similarly arced edge 189 of the recess 187. The body of the fold-presser is formed with a projection 190 received above the shelf 186 and arranged to 5 press upon the shelf which in turn presses upon the margin being folded for pressing the folded margin against the body of the piece of material. The wall 182 is provided with a rear face 191 with which a face 192 10 of the extension 190 coacts for locating the said movable part of the fold-presser in retracted relation, which in the present exemplification is the normal relation of said movable part. The wall 182 is arranged to 15 swing forwardly so that its forward or initial pressing edge for the margin being folded is at substantial right angles to the normal path of feed of the material. For determining this relation, I prefer to provide the movable part with a shoulder 197 20 which coacts with a shoulder 198 on the body of the fold-presser.

In order to insure that the movable part 25 of the fold-presser shall press upon the inner edge of the fold being made along a straight edge when forming a comparatively wide fold, and to further insure that said movable part shall contact said inner edge when forming convex curves on short radii, 30 I prefer to provide the movable part of the fold-presser with a laterally extending nose 199, whereby I find I am enabled to increase the degree of recession of the initial pressing face of the movable part.

35 For manipulating the movable part of the fold-presser I have exemplified the following instrumentalities, namely: An arm 201 has articulated connection with the movable part of the fold-presser. As shown the arm, 40 201 is provided with a slot 202 by the walls of which a pin 203 on the lever 183 is guided and moved. The arm 201 is part of a lever 204 pivoted on a pivot-screw 205 threaded into a shelf 206 of a bearing 207 clamped about a stud 208 secured in a bearing 209 45 depending from the head of the goose-neck of the frame. This lever swings readily about its pivot and is arranged to be readily manually manipulated, this being shown accomplished by manipulation by the thumb, 50 finger or hand, by means of a push-portion 210 thereof formed by bending the forward end of the lever upwardly. The lever is normally pressed by a spring 211 in a direction 55 for causing retraction of the movable part of the fold-presser. Means are provided for adjusting the extent of this retractive movement or for fixing the path of the initial pressing edge of the movable part 60 in advanced position, accomplished in the present exemplification by an arm 214 pivoted about a pivot-screw 215 threaded into the bracket 206 and frictionally held in adjusted positions by means of a friction- 65 washer 216, this washer in the form shown

being provided with a finger 217 in which one end of the spring 211 is secured, the other end of said spring being received about a hook 218 formed in the push-portion 210 of the lever 204. The arm 214 70 is held in the position to which it may be adjusted about the axis of the pivot-screw 215 by means of the friction-washer 216 sufficiently rigid to prevent its displacement by the retractive movement of the spring, and 75 the friction-washer is held in its place by means of a flat edge 219 thereof received against the bearing 207.

For readily positioning the arm 214 it is provided with a manipulating part 220, 80 shown as an upturned front end thereof, forming a push-plate or handle, which is readily grasped by the thumb or finger or pushed by the finger or thumb in either direction by the operator during the operation of the machine or while the machine is at rest, for adjustably positioning the same about its axis, so as to adjustably limit the extent of retractive movement of the arm 201, for adjusting the limit of retractive 90 movement of the movable part 181 of the fold-presser, or for positioning said movable part in extreme forward position, the reciprocations of the latter in the fold-pressing operation then taking place in this latter position. The arm 214 and lever 204 are respectively provided with coacting contact-parts 221, 222. If desired, the arm 214 may by swung rearwardly out of engaging relation with the lever 204.

100 The lever 204 is primarily for the purpose of manually controlling the movable part of the fold-presser during the operation of the machine, and the arm 214 is provided primarily for the purpose of determining the range of limits of movement of the movable part of the fold-presser, or for causing reciprocations of said movable part in its forward limit of position.

105 While I have shown the forward pressing face of the fold-presser as a normally retreating face, arranged to be changed by the operator to a forward pressing face at substantial right angles to the line of feed, it is of course obvious that the forward pressing 110 face may normally be extended at substantial right angles to the line of feed and arranged to be changed by the operator to a retreating forward pressing face, without departing from the spirit of my invention.

115 Having thus fully described my invention, what I claim as new and desire to secure by Letters Patent, is:

1. A folding machine of the character described comprising in combination means 120 for progressively feeding the material, a fold-presser, and means comprising shifting means for selectively presenting a forward fold-pressing face of said fold-presser in a plane parallel to the face of the pressed 130

- fold recedingly crosswise of said fold or presenting a forward fold-pressing face of said fold-presser in said plane substantially directly across the width of said fold being pressed when in fold-pressing relation.
2. A folding machine of the character described comprising in combination means for progressively feeding the material, a fold-presser, and means under the control of the operator during the progressive feeding of the material for selectively presenting a forward fold-pressing face of said fold-presser crosswise of the fold being pressed so as to retreat in the direction of the feeding movement or presenting a forward fold-pressing face of said fold-presser in a direction more nearly directly across the width of said fold being pressed when in fold-pressing relation.
3. A folding machine of the character described comprising in combination means for progressively feeding the material, a fold-presser, means for reciprocating said fold-presser, and means comprising shifting means for selectively locating a forward fold-pressing face of said fold-presser crosswise of the fold being pressed so as to retreat in the direction of the feeding movement or locating a forward fold-pressing face of said fold-presser in a direction more nearly directly across the width of said fold being pressed when in fold-pressing relation, and adjusting means for said shifting means.
4. A folding machine of the character described comprising in combination means for progressively feeding the material, a fold-presser, means for reciprocating said fold-presser, and means comprising shifting means for selectively locating a forward fold-pressing portion of said fold-presser crosswise of the fold being pressed so as to retreat in the direction of the feeding movement or locating a forward fold-pressing portion of said fold-presser in a direction more nearly directly across the width of said fold being pressed when in fold-pressing relation, and adjusting means under the control of the operator during the progressive feeding of the material for fixing the path of reciprocating movement of the forward fold-pressing face.
5. A folding machine of the character described comprising in combination means for progressively feeding the material, fold-turning means, a fold-presser, and means comprising shifting means for selectively locating a forward fold-pressing portion of said fold-presser crosswise of the fold being pressed so as to retreat in the direction of the feeding movement or presenting a forward fold-pressing portion of said fold-presser in a direction more nearly directly across the width of said fold being pressed when in fold-pressing relation, a material support coacting with said fold-turning means, fold-presser and feeding means, and a material-supporting part elevated above said material-support in advance of said fold-turning means, fold-presser and feeding means for reversely curling the edge of the fold being formed by said fold-turning means.
6. A folding machine of the character described comprising in combination means for progressively feeding the material, a fold-presser, a material-support coacting with said fold-presser and feeding means, an elevated material-supporting part in advance of said first-named material-support, and means for presenting a forward fold-pressing portion of said fold-presser in rear of said raised material-supporting part selectively receding in the direction of the feeding movement crosswise of the fold being pressed or in a direction more nearly directly across the width of the fold being pressed when in fold-pressing relation.
7. A folding machine of the character described comprising in combination means for progressively feeding the material, a fold-presser, a material-support coacting with said fold-presser and feeding means, an elevated material-supporting part in advance of said first-named material-support, and means arranged to be controlled by the operator during the progressive feeding of the material for presenting a forward fold-pressing portion of said fold-presser in rear of said raised material-supporting part selectively receding in the direction of the feeding movement crosswise of the fold being pressed or in a direction more nearly directly across the width of the fold being pressed when in fold-pressing relation.
8. A folding machine of the character described comprising in combination means for progressively feeding the material, a folder for imparting an upward curl to the edge of the material, a fold-presser, a material-support coacting with said folder and fold-presser, a side gage for the edge of the material being fed located in advance of said folder, and an elevated material-supporting part in advance of said first-named material-support for reversely curling and thereby deflecting said edge toward said side-gage.
9. A folding machine of the character described comprising in combination means for progressively feeding the material, a folder for imparting an upward curl to the edge of the material, a fold-presser, a material-support coacting with said feeding means, folder and fold-presser, a side-gage for the edge of the material being fed located in advance of said folder, an elevated material-supporting part in advance of said first-named material-support for reversely curling and thereby deflecting said edge to-

ward said side-gage, the material-supporting parts having a depression between said elevated material-supporting part and said side-gage, and a finger located above said depression.

5 10. In a folding machine of the character described, the combination of progressively acting feeding means for the material, a reciprocating fold-pressing part arranged to press the margin being folded pivoted on an axis substantially perpendicular to the plane of the pressed margin of the material when said fold-pressing part is in pressing relation, and means for shifting said fold-pressing part about said axis for presenting its fold-pressing face in different directions crosswise of the margin being folded.

15 11. In a folding machine of the character described, the combination of feeding means for the material, a reciprocating fold-pressing part arranged to press the margin being folded pivoted on an axis substantially perpendicular to the plane of the pressed margin of the material when said fold-pressing part is in pressing relation, and means for shifting said fold-pressing part about said axis for presenting its fold-pressing face in different directions crosswise of the margin being folded, said fold-pressing part being 20 provided with a laterally extending fold-pressing nose at its outer end.

25 12. In a folding machine of the character described, the combination of feeding means and margin-turning means for the material, a reciprocating fold-pressing part arranged to press the margin being folded pivoted on an axis substantially perpendicular to the plane of the pressed margin of the material when said fold-pressing part is in pressing 30 relation, means for shifting said fold-pressing part about said axis for presenting its fold-pressing face in different directions crosswise of the margin being folded, a side-gage for the edge of the material, and a material contact part under said material acting 35 on said material in advance of said margin-turning means adjacent to said edge for bulging the said material upwardly and thereby deflecting said edge downwardly.

40 13. In a folding machine of the character described, the combination of progressively acting feeding means and margin-turning means for the material, and a reciprocating fold-pressing part having a forward fold-pressing face and a pivotal axis which is substantially perpendicular to the plane of the pressed margin of the material when said fold-pressing part is in pressing position for presenting said fold-pressing face selectively in a plurality of directions crosswise of said pressed margin.

45 14. In a folding machine of the character described, the combination of progressively acting feeding means for the material, a reciprocating fold-pressing part having a for-

ward fold-pressing face and a pivotal axis which is substantially perpendicular to the plane of the pressed margin of the material when said fold-pressing part is in pressing position for presenting said fold-pressing 50 face selectively in a plurality of directions crosswise of said pressed margin, and means under the control of the operator during the feeding movements of the material for shifting said fold-pressing part about its pivot.

55 15. In a folding machine of the character described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said fold-pressing 60 face selectively in a plurality of directions crosswise of said pressed margin, means arranged to be moved by the operator during the feeding movements of the material for shifting said fold-pressing part about its pivot, and adjusting means 65 for adjustably fixing the path of reciprocating movement of said reciprocating forward fold-pressing face.

70 16. In a folding machine of the character described, the combination of progressively acting feeding means for the material, a reciprocating fold-pressing part having a forward fold-pressing face and a pivotal axis which is substantially perpendicular to the plane of the pressed margin of the material 75 when said fold-pressing part is in pressing position for presenting said fold-pressing face selectively in a plurality of directions crosswise of said pressed margin, and means arranged to be moved by the operator during the feeding movements of the material for adjustably fixing the path of reciprocating 80 movement of said reciprocating forward fold-pressing face.

85 17. In a folding machine of the character described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said fold-pressing 90 face selectively in a plurality of directions crosswise of said pressed margin, means arranged to be moved by the operator during the feeding movements of the material for adjustably fixing the path of reciprocating movement of said reciprocating forward fold-pressing face.

95 18. In a folding machine of the character

described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said forward fold-pressing face selectively in a plurality of directions crosswise of said pressed margin, and resiliently yielding means under the control of the operator during the feeding movements of the material for shifting the said fold-pressing part about its pivot.

19. In a folding machine of the character described, the combination of progressively acting feeding means for the material, a reciprocating fold-presser having a forward fold-pressing face and a pivotal axis which is substantially perpendicular to the plane of the pressed margin of the material when said fold-presser is in pressing position for presenting said forward fold-pressing face selectively in a plurality of directions crosswise of said pressed margin, and means under the control of the operator during the feeding movements of the material for shifting said fold-pressing part about its pivot, said last-named means including resilient means tending to normally move said fold-pressing part to one limit of its shifting movement.

20. In a folding machine of the character described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said forward fold-pressing face selectively in a plurality of directions crosswise of said pressed margin, means under the control of the operator during the feeding movements of the material for shifting said fold-pressing part about its pivot, said last-named means including resilient means tending to normally move said fold-pressing part to one limit of its shifting movement, and adjusting means for adjusting said last-named limit of movement.

21. In a folding machine of the character described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said forward fold-pressing face selectively in a plurality of directions crosswise of said pressed margin, means under the control of the operator during the feeding movements of the material for shifting said fold-pressing part about its pivot, said last-named means including resilient means tending to normally move said fold-pressing part to one limit of its shifting movement, and adjusting means for adjusting said last-named limit of movement.

material for shifting said fold-pressing part about its pivot, said last-named means including resilient means tending to normally move said fold-pressing part to one limit of its shifting movement, and means under the control of the operator during the feeding movements of the material for adjusting said last-named limit of movement.

22. In a folding machine of the character described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said forward fold-pressing face selectively in a plurality of directions crosswise of said pressed margin, and means under the control of the operator during the feeding movements of the material for shifting said fold-pressing part about its pivot, said last-named means including resilient means tending to normally move said fold-presser to one limit of its shifting movement, and adjusting means for positioning said reciprocating fold-presser in a path adjacent to its other limit of shifting movement.

23. In a folding machine of the character described, the combination of progressively acting feeding means for the material, a reciprocating fold-pressing part having a forward fold-pressing face and a pivotal axis which is substantially perpendicular to the plane of the pressed margin of the material when said fold-pressing part is in pressing position for presenting said forward fold-pressing face selectively in a plurality of directions crosswise of said pressed margin, means under the control of the operator during the feeding movements of the material for shifting said fold-pressing part about its pivot, and edge snipping means adapted for snipping the edge being folded when said fold-pressing part is adjacent to its rearward limit of shifting movement. 95 100 105 110

forward limit of shifting movement. 115
24. In a folding machine of the character described, the combination of progressively acting feeding means and margin-folding means for the material, a reciprocating fold-presser comprising a body and a part having a forward fold-pressing face shiftably mounted on said body, said part being provided with a shelf received under said body adapted to be pressed by said body upon the margin being folded, and means under the control of the operator during the feeding of the material for shifting said movable part. 120 125

25. I: a folding machine of the character described, the combination of progressively acting feeding means and margin-folding means for the material, a reciprocating fold-presser comprising a body and a part 130

having a forward fold-pressing face shiftably mounted on said body, and means under the control of the operator during the feeding of the material for shifting said 5 movable part, for selectively presenting a forward fold-pressing face crosswise of the fold being pressed so as to retreat in the direction of the feeding movement or presenting a forward fold-pressing face in a 10 direction more nearly directly across the

width of said fold being pressed when in fold-pressing relation.

In testimony whereof, I have hereunto signed my name, in the presence of two subscribing witnesses.

WILLIAM F. LAUTENSLAGER.

Witnesses:

CHARLES E. WEBER,
THERESA M. SILBER.
